PORTABLE COLLAPSIBLE CRIB

Robert Lerner, 1000 Northfeld Road,
Woodmere, N.Y. 11598

Filed Jan. 13, 1966, Ser. No. 592

Term of patent 14 years

(Cl. D5—5)

FIG. 2 is a flat open perspective view thereof, and
FIG. 3 is an assembled perspective view.
The bottom surface is plain and unornamented.
I claim:

The ornamental design for a portable collapsible crib, substantially as shown and described.
